US0D1044581S

(12) **United States Design Patent** (10) Patent No.: **US D1,044,581 S**
(45) Date of Patent: ** Oct. 1, 2024

(54) **EARRING COMPONENT**

(71) Applicant: **Venus by Maria Tash, Inc.**, New York, NY (US)

(72) Inventor: **Maria Tashjian**, New York, NY (US)

(73) Assignee: **Venus by Maria Tash, Inc.**, New York, NY (US)

(**) Term: **15 Years**

(21) Appl. No.: **29/839,092**

(22) Filed: **May 18, 2022**

(51) LOC (14) Cl. **11-01**

(52) U.S. Cl.
